PACKING BOX

Gerard L. Studley, Walpole, Mass., assignor to
 Bird & Son, inc., East Walpole, Mass., a corporation of Massachusetts

Application July 8, 1939, Serial No. 283,418

1 Claim. (Cl. 217—70)

This invention relates to packing boxes and specifically to boxes of the so-called wood frame construction having side walls of thin material, such as ply wood, fibreboard, or corrugated board 5 reenforced by a wooden frame. Boxes of this general type reenforced by frame members along the corners thereof are in current use, usually with an additional wooden strip or reenforcing clip affixed across the middle of each side wall 10 for the purpose of preventing the outward bulging of the thin side wall material. When such reenforcing cleats are nailed through the wall material to affix them in position, the result is not entirely satisfactory because the ends of the 15 reenforcing cleats are frequently forced outwardly with the bulging side walls and thus become practically useless as a reinforcement. Attempts have been made to overcome this difficulty by driving nails through the perimeter or frame 20 cleats and into the ends of reenforcing cleats, and, also, reenforcing cleats have been held by means of a U-shaped metal clip over the ends of the reenforcing cleat. These methods are either somewhat costly and troublesome to assemble, or, 25 do not provide a box of sufficient strength. This invention provides an improved packing box of simple and effective construction in which the reenforcing cleats are firmly held in position, and thus prevent bulging, the reenforcing cleats being affixed to the perimeter or frame cleats as 30 will hereinafter appear.

In the drawing illustrating the preferred embodiment of the invention,

Fig. 1 is a perspective view showing the complete packing box of this invention;

Fig. 2 is a view taken on line 2—2 of Fig. 1, partly in cross-section, showing in detail the fastening of the reenforcing strips to the frame members;

Fig. 3 is a perspective view of the reenforcing member employed in the packing box of this invention; and

Fig. 4 is a perspective view of a modified form of reenforcing member.

Referring to the drawing in which like numerals represent like parts, the packing box has walls 2 of ply wood, fibreboard, corrugated board, or the like, reenforced along each longitudinal edge by the wood frame comprising perimeter members 4, reenforced across the middle of the side walls by means of reenforcing cleats 6 which may be and preferably are nailed to the side walls 2 by means of nails passing through said side walls and into the cleats, with the heads of the nails on 55 the inside of the thin side wall material. The

ends of the reenforcing cleats are held in position, as shown in Figs. 1 and 2, by means of a formed metal clip, preferably as shown in Fig. 3, and generally designated 7. One end 8 of the reenforcing clip is provided with a hole through which the nail 9 is driven into the reenforcing cleat and the other end 10 is bent downwardly between the end surface of the reenforcing cleat and the abutting surface of the adjacent perimeter cleat 2, though with the toothed or pointed end 10 of the metallic clip bent so as to have the points thereof embedded in the cleat 2 and there held by means of the end of the reenforcing cleat and preferably also by the nail or nails 11, which may be conveniently driven in place at the time 15 of the attachment or embedding of the toothed end of the clip prior to the placing of the reenforcing strip in position, and there nailing it from the inside and by means of the nails 9 passing through the portions 8 of the clips at the 20 respective ends of the reenforcing cleats 6. The clips and reenforcing cleats 6 assist each other in holding the box in its assembled organization inasmuch as the serrated ends of the clips can not be withdrawn because they are locked in 25 place by the ends of the reenforcing cleats 6, and, also, as will be seen from the drawing, the ends of the reenforcing cleats can not move outwardly because of the portions 8 of said clips which are 30 firmly held thereto by the nails 9 which prevent sidewise movement of the cleats.

Similarly, the modified metallic clip structure of Fig. 4 has a portion 8a which overlies and is held to a reenforcing cleat 6 as by a staple 9a and the pointed ends 10a (corresponding to the 35 toothed ends of Fig. 3) may be driven into an adjacent abutting perimeter cleat 2 and there held by staples 11a.

It will be evident that the above construction provides a simple, effective, and strongly constructed packing box with the advantages above set forth.

Having described my invention, what I wish to claim by Letters Patent is:

A wood frame packing box having thin side 45 walls, external wooden cleats reenforcing the perimeter of each side wall constituting perimeter members, reenforcing cleats across side walls of said box connecting and lying entirely between the opposite inner side faces of said perimeter members, said reenforcing cleats being held at the ends thereof to the perimeter members by metallic clip members providing exposed portions 50 overlying and affixed to the outside of each of said ends of the reenforcing cleats and having 55

intermediate portions bent at right angles to said exposed portions and lying between said reinforcing cleat and said perimeter members, said intermediate portions extending inwardly less than the thickness of said perimeter members and having on the ends thereof and at right

angles thereto integral toothed portions embedded in the perimeter members opposite the ends of said reinforcing cleats and thereby held in said perimeter members.
